MISSOURI.

RETAINING-GUIDE FOR COUNTERWEIGHT-ROPES.

1,261,124.

Specification of Letters Patent.

Patented Apr. 2, 1918.

Application filed October 21, 1915. Serial No. 57,129.

To all whom it may concern:

Be it known that we, JOHN LYLE HARRINGTON, ERNEST E. HOWARD, and LOUIS R. ASH, citizens of the United States, residing at Kansas City, in the county of Jackson and State of Missouri, have invented certain new and useful Improvements in Retaining-Guides for Counterweight-Ropes; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to a retaining guide for counterweight ropes and more particularly to a device of this character for use on ropes connecting a movable bridge span with its counterpoise weight, the principal object of the invention being to limit the spreading of the several connecting ropes at a point closely adjacent the equalizer, whereby the ropes are connected with the weight or span, and thereby overcome the loss of energy required for concentrating the ropes as the equalizer approaches the overhead sheave wheel and the resultant pivoting of the equalizer members.

In accomplishing this object we have provided improved details of structure, the preferred forms of which are illustrated in the accompanying drawings, wherein:

Figure I is a side elevation of one of the towers and part of the span of an ordinary type of lift bridge, showing the counterweight ropes equipped with our improvements.

Fig. II is an enlarged side elevation of part of the counterweight and its supporting ropes, the latter equipped with our improved detaining guide.

Fig. III is an end view of the same.

Fig. IV is a central vertical section of the guide and parts of the counterweight ropes.

Fig. V is a cross section on the line V—V, Fig. IV.

Fig. VI is a detail perspective view of one of the guide blocks.

Referring more in detail to the drawings:

1 designates a tower, 2 the lift span, 3 the overhead sheave wheel, which is preferably grooved to properly guide the ropes during

travel of the span, 4 the counterweight, and 5 the connecting ropes of a lift bridge of any ordinary construction and which, as they in themselves form no part of the present invention, are not described in detail. In the present illustration of the invention the equalizer is shown at the weight end of the ropes 5 and the ropes connected with the span. In order to better disclose the construction and operation of our improvement we have illustrated a type of equalizer and will describe its construction in some detail, with the understanding that the construction or particular location of the equalizer forms no part of the present invention.

In its illustrated form the counterweight 4 consists of paired units 9—9', having head plates 10—10' at their upper ends, through which the shafts 11—11' are projected to carry the equalizer, as presently described.

The equalizer, whereby the ropes 5 are connected with the counterweight, consists of primary bars 13—13' which are pivotally mounted on the ends of the shafts 11—11', and as the bars and the parts connected therewith are identical on the separate weight members, we will describe but one in detail, with the understanding that such description relates equally to both.

The bar 13 is substantially triangular in shape and is pivotally mounted at one of its apices on the bolt 11, and pivotally mounted on pins 14—14' that are carried at the upper corners of the bar 13, are paired, secondary plates 15—15' that are substantially similar in construction to the primary bars 13 in that they are triangular in shape and have base parts at the top, one of the secondary plates being located on each side of the bar 13, so that the latter lies between the paired secondary plates.

Extending through the upper corners of the bars 15—15' are bolts 16—16' and pivotally mounted on said bolts are links 17—17', having upper and lower lips extending at right angles to each other, so that the lower lips may be nested between the bars 15—15' while the upper lips 18—18' may extend transversely relative to the weight 9—9'.

Pivotally mounted on pins 19—19' that are carried by the links 18 are bars 20—20', and mounted on spaced pins 21—21' (Fig. III) that are carried by said bars, are socket members 22—22', comprising lip members 110

23—23', that are located between the bars 20—20', and upper socket members 24—24' within which the lower ends of the cable ropes 5 are secured and permanently anchored.

It is apparent that the equalizer that has been described is one adapted for supporting a two-unit counterweight from sixteen cables or ropes, eight of which are run to each end 10 of the weight member, and thus by including said equalizer in the connection between the span and counterweight inequalities in the individual members of the connectors may be automatically compensated by shifting of the equalizer members.

As the equalizer mounting is of substantial width, it is apparent that the flexible connection, usually comprising ropes or cables, would extend fanlike from the sockets and that as the equalizer approaches the upper limit of its travel, upon movement of the span, the ropes approach a perpendicular plane, tangential to the sheave wheel 3, thereby shortening the fan by drawing the 25 ropes toward the perpendicular line of suspension from the point of contact with the sheave wheel, and causing the equalizer members to pivot on the several supports as the fan is shortened, the said parts again pivoting on their mounting as the span is moved in the opposite direction.

As this play of the ropes or cables and the pivoting of the equalizer members represents work which must be accomplished by the 35 mechanism by which the span is raised and lowered, we have sought to provide means for limiting such work to a minimum and also to limit the necessity for lubrication of the equalizer parts and the possibility of 40 noisy operation, by limiting the fan-like spread of the ropes to a minimum and fixed length, and in accomplishing the object of the invention we have provided a clamp that is adapted for permanent attachment to the 45 ropes and for holding same in a fixed spreading relation to each other, so that they extend in straight lines from the sheave wheels to a point closely approaching the equalizer, but without interfering with the equalizing 50 movement.

The preferred form of guide which is illustrated in the drawings, consists of 55 paired blocks 25—25', having curved face plates 26—26' provided with longitudinal grooves 27—27' of the required concavity to snugly seat the ropes 5, and having stiffening end portions 28—28' and transverse ribs 29—29'. The end portions 28—28' of the 60 separate block members are connected by the end plates 30 which are secured to the blocks by bolts 31 that run through the ends plates at opposite ends of the block and through the end portions 28—28', the connection being so arranged that the upper ends of the 65 block members mate, with the grooves

27—27" in registration, so that the ropes 5 may seat in the grooves and lie snugly in the tapered channel formed by the co-operating, flared face plates of the respective blocks.

With the guide adapted for use on the 70 sixteen rope equalizer shown in the drawings, each face plate will comprise sixteen separate grooves 26—26' so that there may be one groove for each individual rope, the ropes that lead to the equalizer member on 75 one of the weights 9—9' lying in the grooves in the face plate on the block at that side of the guide and the ropes leading to the equalizer member on the other weight lying in the opposite face plate, so that each rope 80 may seat freely in an individual groove throughout the length of the block.

In order to prevent the guide from creeping upwardly under the spreading tension of the ropes, we provide an anchor comprising 85 rods 32—32' which are pivotally suspended from the end plates 30, preferably by yokes 33—33' and carry a cross bar 34 at their lower ends, preferably by means of the yokes 35—35' that are fixed to the rods and 90 pivotally mounted on the pins 36—36' on the cross bar, each of said rods being also preferably provided with a turnbuckle 37 whereby the guide may be adjusted to tighten or loosen the ropes.

Pivotally mounted on the cross bar, also 95 preferably by means of yokes 38—38', are rods 39—39' which lie on opposite sides of the equalizer bars and are anchored to the base members 40—40' that are carried by 100 the shaft 11—11' on the separate weight members 9—9', preferably by having their lower ends extended through apertures on the lower flange of the base members and provided with nuts 41—41' that bear against 105 the under faces of said flanges.

Assuming that a bridge of the character described is equipped with a counterweight connection having an equalizer like the one illustrated in the drawing, or similar thereto, 11 and it is desired to equip the same with our improved rope retaining guide, the separate guide members are applied to the ropes at a point directly above the equalizer and drawn together until the ropes seat in the grooves 11 27—27' and are confined by the upper ends of the spaced plates 25—25' so that they may move freely in the guide without escaping therefrom. The ropes are held in such position while the end plates 30 are 1 bolted to the body members of the guide to hold the plates 25—25' in place and anchor the same to the ropes, the separate clamp members being suitably held to the ropes during the tightening process in order to prevent their slipping longitudinally therealong under the increased strain due to spreading tension of the ropes.

When the guide has been applied to the ropes as described, the anchor rods 32—32'

are connected with the end plates of the guide and the rods 39-39' are anchored to the base rails 40-40', so that the guide is held against longitudinal creeping movement along the ropes, the turnbuckles 37-37' being afterward used, when necessary, to tension the guide by drawing the same along the ropes toward the equalizer.

It is apparent that with the ropes held as described, they will hang perpendicularly from their point of contact with the sheave wheel, but may spread between the guide and the equalizer, so that when the equalizer approaches the upper limit of its travel, the ropes will contact the sheave wheel on a perpendicular tangent and that the spread of the ropes will be limited to the parts between the clamp and the equalizer, so that there will be slight pivotal movement of the equalizer members during the movement of the equalizer at the upper portion of its travel. It is also apparent that the ropes are held loosely by the guide, so that while their spread is limited, they may have free longitudinal movement in the guide to effect the automatic equalization heretofore mentioned.

Having thus described our invention, what we claim as new therein, and desire to secure by Letters-Patent, is:

1. A rope retaining guide comprising spaced face plates curved from the same end of the device to form a flaring channel having a confining neck and a relatively wide mouth, the said face plates having longitudinal grooves therein forming rope seats substantially as set forth.

2. A retaining guide comprising separate block members each having a curved face plate and means connecting said blocks to retain the face plates in spaced relation, the curvature of the face plates forming a narrow channel therebetween at one end of the guide and a relatively wide flaring mouth at the opposite end of the guide.

3. A rope retaining guide comprising separate blocks, each comprising a curved face plate and integral end flange, and end plates attached to said flanges and retaining the face plates in spaced relation, with the curved faces of the face plates forming a flared channel between the blocks.

4. A rope retaining guide comprising separate blocks, each comprising a curved face plate and integral end flange, end plates at-

tached to said flanges and retaining the face plates in spaced relation, with the curved faces of the face plates forming a flared channel between the blocks, and means connected with said end plates for anchoring the guide.

5. A rope retaining guide comprising separate blocks, each comprising a curved face plate and integral end flange, end plates attached to said flanges and retaining the face plates in spaced relation, with the curved faces of the face plates forming a flared channel between the blocks, means connected with said end plates for anchoring the guide, the said face plate having longitudinal grooves for seating the rope substantially as set forth.

6. A retaining guide comprising separate blocks, each having a curved face plate provided with longitudinal grooves and means for retaining said blocks in spaced relation, with the grooves of opposite face plates registering and the plates lying in close relation at one end of the blocks to form a restricted neck and flared toward the opposite end of the block to form a mouth substantially as set forth.

7. The combination with a tower, of an overhead sheave wheel on the tower, a lift span and counterweight, equalizer shafts on the counterweight, an equalizer mounted on the shafts, ropes connected with the equalizer, a retaining guide on said ropes, base bars on said shafts, rods connected with the retaining guide, rods pivotally connected with the base bars, and a cross bar pivotally connecting the retaining guide and base bar rods.

8. The combination with a tower, of an overhead sheave wheel on the tower, a lift span and counterweight, equalizer shafts on the counterweight, an equalizer mounted on said shafts, ropes connected with the equalizer, a retaining guide on said ropes, base bars on said shafts, rods connected with the retaining guide, rods pivotally connected with the base bars, and a cross bar pivotally connecting the retaining guide and base bar rods.

In testimony whereof we affix our signatures.
